Primary Examiner — Sheryl Lane*Assistant Examiner* — Alex T. Milbrath(74) *Attorney, Agent, or Firm* — Xiaofang Zhong(57) **CLAIM**

The ornamental design for a lamp component, as shown and described.

DESCRIPTION

FIG. 1 is a front, right and top perspective view of a lamp component showing my new design;

FIG. 2 is a rear, left and bottom perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof; and,

FIG. 8 is a bottom plan view thereof.

The lamp component is shown with a symbolic break in its length. The appearance of any portion of the article between the break lines forms no part of the claimed design.

1 Claim, 8 Drawing Sheets(56)
